UNITED STATES PATENT OFFICE

128,070

DESIGN FOR A VEST OR SIMILAR ARTICLE

David J. Rosenberg, New York, N. Y.

Application May 27, 1941, Serial No. 101,178

Term of patent 3½ years

To all whom it may concern:

Be it known that I, David J. Rosenberg, a citizen of the United States of America, residing in New York city, county of New York and State of New York, have invented a new, original, and ornamental Design for a Vest or Similar Article, of which the following is a specification, reference being had to the accompanying drawing, forming part thereof, wherein,

Figure 1 is a front view of a vest or similar article showing my new design, and

I claim:

The ornamental design for a vest or similar article, substantially as shown.

DAVID J. ROSENBERG.
